CLAIM

The ornamental design for a chair cover, as shown and described.

DESCRIPTION

FIG. 1 is a top plan view of a chair cover showing our design;

FIG. 2 is a side view;

FIG. 3 is a front view;

FIG. 4 is a rear view;

FIG. 5 is a cross sectional view taken along the lines 5—5 of FIG. 3; and

FIG. 6 is a front perspective view thereof.

The chair as shown by means of the broken lines in FIG. 5 is for illustrative purposes only.
